TELEVISION APPARATUS

Frank Conrad, Wilkinsburg, Pa., assignor to Westinghouse Electric & Manufacturing Company, a corporation of Pennsylvania

Application January 18, 1929, Serial No. 333,374

6 Claims. (Cl. 178—6)

My invention relates to television and more particularly to a radio transmission system for causing distant images to appear upon a screen.

The object of my invention is to provide improved apparatus for synchronizing the scanning discs in a system of the above-mentioned type.

A further object of my invention is to provide a receiving apparatus for projecting the transmitted image upon a screen.

A still further object of my invention is to provide an improved scanning-disc structure.

A still further object of my invention is to provide an improved system for simultaneously transmitting images from a plurality of widely spaced transmitters.

In practicing my invention, I employ scanning discs at transmitting and receiving stations, the scanning discs being driven by synchronous motors controlled by a single source of alternating current having a comparatively high frequency, preferably a frequency near the upper limit of the audio frequency range utilized in broadcasting musical programs. The frequency of the current from the same alternating-current source is multiplied and the current transmitted from the transmitting stations as a carrier wave. The alternating current is maintained at a constant frequency by means of a system including an electric clock and a synchronous motor which, periodically, applies heat to a tuning fork, as will be more fully described hereinafter.

Instead of employing a synchronous motor of the usual type for driving a scanning disc, a soft-iron ring, having teeth on its outer edge, is attached to the scanning disc so that the scanning disc itself constitutes a part of the rotor of the synchronous motor.

By employing a mercury-arc lamp or a gas lamp, such as a neon lamp, connected to the output of the receiving apparatus through a specially designed circuit, a light of sufficient intensity is obtained to throw a view of the transmitted image upon a screen. In this way, a picture of larger dimensions is obtained than has been possible with most systems formerly constructed.

Other features and advantages of my invention will appear from the following description, taken in connection with the accompanying drawings in which:

Figure 1 is a diagrammatic view of the apparatus and electrical connections employed in a system constructed in accordance with my invention;

Fig. 2 is an end elevational view of a scanning disc and a synchronous motor constructed in accordance with my invention;

Fig. 2a is a view of a minor portion of a modified form of the scanning disc and motor shown in Fig. 2.

Fig. 3 is a sectional view, taken along a line corresponding to the line III—III of Fig. 2;

Fig. 4 is a side elevational view of a scanning disc and its driving motors;

Fig. 5 is a diagrammatic view of the apparatus and electrical connections employed in the constant-frequency generator constructed in accordance with my invention;

Fig. 6 is a diagram to aid in describing the operation of the constant-frequency generator;

Fig. 7 is a diagrammatic view of the heating box and heating apparatus for the constant-frequency-generator tuning fork;

Fig. 8 is an end elevational view of the tuning fork and its holder and driving mechanism;

Fig. 9 is a sectional view, taken along a line corresponding to the line IX—IX of Fig. 8.

Referring to Fig. 1, the system comprises two widely spaced transmitting stations—station A and station B—with their corresponding receiving stations—station A' and station B'.

A carrier wave of frequency f_2 is supplied from a source 1 of alternating current having a substantially constant frequency, preferably above the range commonly utilized when transmitting musical programs, and a frequency multiplier 2. The frequency employed in the example being described is 5000 cycles per second. The frequency of the 5000-cycle current is multiplied to the frequency f_2 by any suitable frequency multiplier 2 and the current then supplied to an amplifier-modulator 3. An example of a frequency multiplier which may be employed in my system is described in Patent 1,646,438 granted October 25, 1927 to H. A. Affel.

The picture current, containing a range of frequencies represented by f_p , is also supplied to the amplifier-modulator 3, and the resulting modulated carrier, represented by $f_2, f_2 \pm f_p$, is supplied to a transmitting antenna 4 by any suitable coupling means 5 and radiated. The picture current of frequency f_p is obtained by means of apparatus including a scanning disc 6 and a photoelectric cell 7. The scanning disc 6 is of a well known type having holes located in a spiral around its periphery, as shown in detail in Figs. 2 and 3. A beam of light from a light source 8 is passed through these holes upon the image 9 to be transmitted and is reflected to the photoelec-

tric cell 7, the current output of which varies in accordance with the light intensity. The scanning disc 6 is rotated at a high speed by means of a synchronous motor 10 of the phonic-wheel type connected to the 5000-cycle source 1 by means of a metallic line 11 and amplifiers 12 and 13.

A carrier current f_1 is modulated by the 5000-cycle current and radiated from an antenna as the modulated carrier wave $f_1, f_1 \pm 5000$. The apparatus for transmitting the modulated carrier wave $f_1, f_1 \pm 5000$ comprises an amplifier-modulator 14 to which is connected an oscillator-generator 15, supplying a current of frequency f_1 , and the 5000-cycle generator 1. The amplifier-modulator 14 is connected to an antenna 16 by any suitable coupling means 17.

The receiving station A' comprises a scanning disc 18, similar to that at the transmitting station, and a source of light 19, the intensity of which is varied in accordance with the modulated carrier wave f_2 . The modulated carrier wave f_2 is picked up by the receiving antenna 20, demodulated by a detector 21, and the resulting picture current f_p amplified by a vacuum-tube amplifier 22 and impressed upon a mercury-arc lamp 23 through a step-down transformer 24 and a condenser 25. The mercury-arc lamp 23 is connected to a direct-current supply through an inductance 26, a resistance 27 and a connection 28.

The scanning disc 18 is driven by a synchronous motor 29, similar to motor 10, connected to a circuit 30 which receives and demodulates the modulated carrier wave f_1 . By means of this circuit, the carrier wave f_1 is picked up by the antenna 31, demodulated by a detector 32, and the resulting 5000-cycle current passed through an amplifier 33 and a 5000-cycle filter 34 to the synchronous motor 29. Consequently, the scanning disc 18, at the receiving station, is run in synchronism with the scanning disc 6 at the transmitting station, and a reproduction of the image 9 appears on a screen 35. Obviously, the scanning discs 6 and 18 will remain in synchronism so that the image will be reproduced even though the frequency of the constant-frequency-generator output varies slightly.

The utilization of a mercury-arc lamp 23, as illustrated, is desirable since it is possible to cause a wide variation in the light intensity by means of a comparatively small energy output from the amplifier 22 in the radio-receiver circuit. This is possible because the characteristic of a mercury-arc lamp is such that the voltage impressed across the tube electrodes remains nearly constant even though the value of the current passing through the tube varies widely. For example, if the current consumption of a tube is 4 amperes, with a direct-current voltage of 50 volts impressed upon the tube electrodes, the current through the tube may be decreased to 3 amperes or increased to 5 amperes by a change of only 1 or 2 volts in the applied direct-current voltage. Accordingly, by employing the step-down transformer 24, a comparatively high secondary current having a small voltage variation can be obtained from the thermionic-tube amplifier 22 and employed to produce large current changes in the mercury-arc lamp 23.

Since gas lamps, such as the neon lamp, have characteristics similar to the mercury-arc lamp, they may be substituted for the mercury lamp, if desired.

A step-down-transformer ratio of 20 to 1 has been found satisfactory, although, obviously, the

ratio may vary within wide limits and should be determined by the characteristics of the particular lamp being employed. The values of capacity, inductance, resistance and direct-current-voltage supply employed in the circuit, likewise, are not critical. The following values have been found satisfactory: condenser 25, 300 microfarads; inductance 26, 3 henries; resistance 27, 100 ohms; and D. C. voltage supply, 110 volts.

The transmitting station B is employed for broadcasting the image 9 located at the station A over a section of the country remote from the section covered by station A. Station B transmits on a carrier wave having the same frequency as that transmitted from station A. This carrier wave is obtained by receiving the modulated carrier wave f_1 on an antenna 36, demodulating it by a detector 37, and multiplying the frequency of the resulting 5000-cycle current by a frequency multiplier 38. The resulting carrier wave f_2 is impressed upon an amplifier-modulator 39, modulated by the picture current f_p which is supplied to the amplifier-modulator 39 from the station A over a metallic line 40, and transmitted from an antenna 41.

A radio repeater station 42, located in the vicinity of station B, broadcasts a carrier wave f_3 modulated by the 5000-cycle current, represented by $f_3, f_3 \pm 5000$, for driving the scanning discs at the receiving station B' located in the vicinity of station B. The repeater station 42 is of the well known type which receives a modulated carrier wave of one frequency, amplifies it, changes the frequency of the carrier wave and re-radiates it. In the circuit illustrated, the modulated carrier f_1 is picked up by a receiving antenna 43, transmitted to the amplifying and frequency-changing unit 44 through a transformer or other coupling device 45 and re-radiated from a transmitting antenna 46.

The receiving station B', which receives the image 9 transmitted from station B, is identical with receiving station A', except for the fact that the receiving circuit is tuned to the carrier-wave frequency f_3 instead of to the frequency f_1 .

One of the main reasons for choosing a frequency of 5000 cycles per second for driving the scanning discs is that it is a frequency to which radio-broadcast receivers are comparatively insensitive, while, at the same time, it is a frequency which can be transmitted over a high grade telephone line and through the repeater apparatus associated therewith. The metallic line 11 connecting the 5000-cycle supply 1 to the synchronous motor 10 at station A may be several miles in length, since the studio or the event to be transmitted may be located a considerable distance from the transmitting station proper. In view of this fact, it is both economical and convenient to have a system in which existing telephone lines and their associated apparatus may be utilized, either without modification or with the associated apparatus only slightly modified.

The fact that the frequency of 5000 cycles per second is one to which radio receivers are comparatively insensitive is important, because the selectivity of radio receivers is not great enough to separate closely adjacent carrier frequencies. For this reason, the carrier wave which is modulated by the 5000-cycle current may, in some instances, be passed through a radio receiver and demodulated so that the 5000-cycle note will appear in the output when it is desired to receive

and demodulate a different carrier frequency modulated by speech or music. The 5000-cycle frequency, however, is so high that it is above the frequency range which includes the frequencies necessary for properly reproducing speech and music. Since the radio receiver is designed for receiving only the frequencies included within the speech and music range, it will not amplify the 5000-cycle note as efficiently as lower notes and, consequently, this note will not be objectionable in the receiver output.

Frequencies in the neighborhood of 5000 cycles per second are not only unnecessary for properly reproducing music, but, in fact, often include the frequencies of undesirable noise. For this reason, many radio receivers and loud speakers are designed to cut-off at a frequency below 5000 cycles per second.

At the same time, a frequency of 5000 cycles per second is not so high but what it can be transmitted over a telephone line designed for transmitting musical programs. Even though the telephone line may not efficiently transmit a current of this frequency, sufficient amplification may be used for effective transmission. Furthermore, frequencies in the neighborhood of 5000 cycles per second are low enough so that a telephone line can easily be modified, if necessary, to transmit them.

The frequency determined by the above limitations has further advantages in that it permits the employment of a synchronous-motor rotor having approximately the same diameter as that of the scanning disc. This makes possible the use of a synchronous motor having so many rotor teeth that it may slip one rotor tooth and yet not shift the image too much to one side on the screen.

It also permits the utilization of the frequency of 5000 cycles per second, the harmonics of which may be employed for checking the carrier frequencies of broadcast stations—these carrier frequencies being spaced 10 kilocycles apart. While the harmonics of certain frequencies below 5000 cycles per second (of the frequencies of 1000 and 2000 cycles per second, for example) would include frequencies equal to those of the broadcast carrier waves, the harmonics would be so close together that they could not be readily identified. On the other hand, the frequencies above 5000 cycles per second, which have harmonics suitable for checking broadcast carrier waves, are too high to be transmitted over a telephone line. For these reasons, the 5000-cycle frequency is peculiarly adapted for the double use of synchronizing the scanning disc in a television system of the type above-specified and of checking the frequencies of broadcast carriers.

Referring to Fig. 4, which shows the structure employed at transmitting station A, the scanning disc 6 is mounted on a shaft 47 journaled in supports 48, mounted on a base plate 49. The scanning disc 6 is driven by means of a motor 50 mounted on the base plate 49, the motor 50 being connected to the scanning disc 6 by a belt 51 and by means of a synchronous motor 10. The motor 50 may be of any type the speed of which can be adjusted to drive the scanning disc 6 at approximately the correct speed. The object in employing the motor 50 is to reduce the power which must be furnished by the synchronous motor 10. The synchronous motor 10 has a rotor which comprises a laminated iron ring 52 having teeth on its periphery and so bolted or riveted to the scanning disc 6 that the disc 6 forms part

of the rotor. The stator coils 53 of the synchronous motor 10 are wound on soft-iron pole pieces supported by a member 54 bolted to one of the supports 48. This motor is of the phonic-wheel type and is shown in detail in Figs. 2 and 3.

A vibration dampener 55 for reducing the effect of hunting of the synchronous motor 10 is employed. The dampener comprises a balance wheel 56 which is loosely mounted upon the shaft 47 but which frictionally engages it by means of asbestos-lined plates 57 rigidly connected to the shaft 47 by means of collars 58 and set screws. The detailed construction of the scanning disc 6 and synchronous motor 10 is shown in Figs. 2 and 3.

An example is illustrated in Figs. 2 and 3 in which the scanning disc 6 comprises a disc of metal or any other suitable material having 60 holes located around its periphery in the form of a spiral. Because of the difficulty of making square holes of the desired smallness in a disc thick enough to withstand the required high speed of rotation, comparatively large holes 59 are drilled in the disc and thin metal plates 60, having small square holes 61 therein, are placed over the large holes 59 and held in position by screws 62. Square holes 61 are punched in the thin plates 60 in order to give the maximum amount of light with maximum detail. After the thin plates 60 have been mounted on the disc 6, the square holes 61 are lined up exactly by optical means.

The synchronous motor 10 for driving the scanning disc 6 includes the scanning disc itself, as part of the rotor, and a rotor element riveted or bolted to the scanning disc. This element comprises a laminated ring 52 of soft iron having teeth 63 projecting from its periphery. In the example illustrated, the rotor has 300 teeth and a synchronous speed, therefore, of 1000 R. P. M. when the 5000-cycle supply 1 is connected to it through a vacuum-tube amplifier. It will be noted that the synchronous speed of the motor is one-half the value it would be if the 5000-cycle current were supplied to it without a direct-current component, since such a component prevents the total current from actually reversing.

The stator of the synchronous motor 10 comprises a laminated arc 64 of soft iron having pole pieces 65 adjacent to the rotor teeth 63. The laminated arc 64 is supported by a member 54 attached to the support 48. A coil 66 is wound on each stator pole 65, and the coils 66 are connected in series in such direction that, at any instant, the adjacent poles are of unlike polarity. In order to provide space for the stator coils 66, there is only one stator pole to every three rotor teeth, the synchronous speed of the motor being determined by the number of rotor teeth. Obviously, the stator may comprise a longer or a shorter laminated arc 64 than the one illustrated or, if desired, it may comprise two or more laminated arcs. The modification illustrated is one of the preferred forms, since the structure necessary for supporting the stator is simple and compact.

In Fig. 2a a modified arrangement of the rotor structure is shown. In this modification, a soft-iron ring 52, having the projecting teeth 63, is mounted outside the spiral of holes 61 in the disc 6 instead of inside the spiral, as shown in Fig. 2. By placing the rotor teeth 63 a greater distance from the axis of the disc 6 in this way, greater synchronizing power may be obtained with a disc of a given diameter. The disadvantage in

volved in employing the modified structure is that, in order to obtain a picture of the same size and having the same detail as is obtained when using the other structure, the scanning holes must be placed in a circumference having the same diameter as that of the holes in that structure. In some cases, therefore, an unduly large disc would be required.

A synchronous motor constructed in the manner above-specified provides an economical and efficient means for driving a plurality of scanning discs in synchronism.

The structure and electrical connections of the 5,000-cycle generator 1 employed in the system 15 described above are shown in Figs. 5, 7, 8 and 9. While a generator which will supply an output having a substantially constant frequency is not essential for synchronizing purposes, it is essential for checking the carrier frequencies of broadcast stations. The apparatus indicated in Fig. 5 20 by the legend "heater and fork" is shown schematically in Fig. 7. It comprises a heat-insulated box 67 within which are located two electric heaters 68 and 69. The upper heater 68 is connected to a source of current through a thermostatic relay 70 of the bimetallic type. A condenser 71 is shunted across the relay contacts to reduce sparking. The interior of the heater box 1 is maintained at substantially a constant temperature by means of the heater 68 and thermostatic relay 70. The heater 69, which may be an ordinary flat-iron heater, is provided for applying heat directly to the tuning fork holder 72, the amount of heat which is applied being controlled by means of the circuit shown in Fig. 5. 25 The elements 73 and 74, connected to the conductors 75 and 76, respectively, are electro-magnetic devices for driving the tuning fork.

The construction of the tuning-fork holder 72, 40 tuning fork, and electro-magnetic driving means 73 and 74 can best be understood by referring to Figs. 8 and 9. The holder 72 comprises two solid metallic blocks 77 and 78, preferably of brass, each having a vertical hole 79 drilled off center, therein. Each block has a larger threaded hole, drilled at right-angles to the vertical hole 79 and communicating with it, in which one of the electromagnetic driving units 73 and 74 is supported. The two blocks 77 and 78 are clamped together by means of bolts 80, with their thin walls adjacent to each other and with a sheet of magnetic material 81 therebetween. In this way, two well portions 79 are formed, separated by a thin partition of magnetic material 81 and 45 non-magnetic material 82. A square notch 83 is cut in the middle of the upper edge of this partition. The tuning fork 84 is clamped, by means of bolts 85, between two solid metal blocks 86 and 87, preferably of brass. Blocks 86 and 87 are secured by bolts 88 to the blocks 77 and 78 in such position that a portion of the tuning fork 50 84 is located within the notch 83 cut in the partition, while the prongs 99 are located within the wells 79. A clip 100 is attached at the top of the block for holding a thermometer 101.

The tuning-fork-driving elements 73 and 74 55 comprise telephone-receiver units having poles adjacent to the prongs 99 of the tuning fork 84. These poles are soft-iron pieces attached to the 60 poles of a permanent magnet 102. They have coils 103 mounted thereon which are connected to the binding posts 104. The driving elements are held in place by means of set screws 105.

75 The partition above-specified is provided for

electrically shielding the driving elements 73 and 74 from each other.

Since the tuning fork 84 is in contact with the brass blocks 86 and 87 which are good heat conductors, the temperature of the fork 84 may 5 be controlled by varying the amount of heat applied to these blocks. This is done by setting the fork holder 72 upon an electric heater 69, as shown in Fig. 7, and by controlling the amount of current flowing through the heater by means of the circuit shown in Fig. 5.

Referring to Fig. 5, the 5000-cycle current is generated by so connecting the fork-driving elements 73 and 74 to an amplifier 106 that the fork 84 is vibrated at its natural frequency. The 15 driving element 74 is connected to the input of the amplifier 106 by conductors 76, while the driving element 73 is connected to the output of the amplifier 106 by conductors 75. By means of this arrangement, the fork 84 is driven at its 20 natural frequency by the energy supplied from the amplifier 106, and a current of this frequency can be obtained from the amplifier output.

The frequency of the current generated is controlled by varying the amount of heat supplied 25 through the heater circuit 107 to the fork heater 69. The amount of heat supplied to the fork 84 is controlled by means of a synchronous motor 108 (preferably of the phonic wheel type) connected to the fork-amplifier output through an 30 amplifier 109, and by means of an electric clock 110.

When a current of the desired frequency is being generated, the synchronous motor 108 connects the fork-heater circuit 107 to a source of 35 current at regular intervals, while the electric clock 110 disconnects the heater circuit 107 from the source at like intervals. In this way, the fork heater 69 is alternately connected to, and disconnected from, the source of current, which, 40 in the example illustrated, is a 110 volt alternating-current supply. The circuit connecting the current supply to the fork heater 69 may be traced from one terminal of the 110 volt source, through a conductor 111, a resistor 112, the armature 113 of a relay 114, a contact of relay 114, an ammeter 115, a second resistance 116, an indicator lamp 117 and resistance 118 in parallel, a conductor 119, one conductor of line 107, the fork heater 69, the other conductor of line 107 45 and the conductor 120, back to the other terminal of the alternating-current supply. The winding of relay 114, which pulls up the armature 113 and thereby connects the fork heater 69 to the alternating-current supply, has one terminal connected to ground and the other terminal connected, through a resistance 121 and a conductor 122, to one terminal of a battery 123, the other terminal of the battery 123 being connected to ground. 55

A polar relay 124, having an armature 125 connected to ground, is provided for connecting the right-hand terminal of the winding of relay 114 to ground through the conductor 126 and relay contact. It is evident that, when the armature 125 of the polar relay 124 rests against the left-hand contact, the armature 113 of the relay 114 is pulled up to connect the fork heater 69 to the 60 110 volt supply. When the armature 125 of the polar relay 124 rests against the right-hand contact, the winding of the relay 114 is short circuited and the armature 113 drops down, thus disconnecting the fork heater 69 from the 110 volt supply. 65

The armature 125 of the polar relay 124 is 70 75

pulled over to the left, to connect the fork heater 69 to the 110 volt supply, each time the upper terminal of the left-hand winding 127 of said relay is connected to ground by means of the synchronous motor 108 through the conductor 128, brush 129, contact element 130, shaft 131, ring 132 and brush 133. The shaft 131 is connected to the synchronous motor 108 through a gear reduction unit so that contact between element 130 and brush 129 is made once every two seconds if the tuning fork 84 is vibrating at the proper frequency.

The polar relay armature 125 is pulled against the right-hand contact, to disconnect the fork heater 69 from the 110-volt supply, each time the electric clock 110 pulls the armature 134 of the polar relay 135 against the left-hand contact. Since the electric clock 110 actuates the polar relay 135 at regular intervals; once every two seconds, in the example illustrated, the fork heater 69 will be disconnected from the 110-volt supply at like intervals. The synchronous motor 108 and the electric clock 110 are so adjusted with respect to each other that they alternately connect and disconnect the fork heater 69 and the current supply. The electric clock 110 is, preferably, of the type described and claimed in my co-pending application, Serial No. 176,061, filed March 17, 1927, in which the pendulum is driven by charging and discharging a condenser through a driving coil. The coil of the polar relay 135 is connected in series with this driving coil.

When the armature 134 is pulled against the left-hand contact, a circuit is completed from a battery 136, through a resistance 137, a conductor 138, a relay winding 139, a conductor 140, the relay armature 134, and the left-hand contact, back to the battery 136. This pulls the relay armature 141 against the upper contact and connects the upper terminal of the right-hand winding 142 of the polar relay 124, to ground through conductor 143 and armature 141. The armature 125 of the polar relay 124 is then pulled against the right-hand contact, and relay armature 113 drops, thereby disconnecting the heater 69 from the current supply.

A special circuit is provided for passing current through the polar relay windings 127 and 142 in response to the closing of either the synchronous motor or the electric-clock contacts. The circuit comprises the battery 123 which is connected, through a conductor 144, a resistance 145 of a few hundred ohms and a second resistance 146 of several megohms, to one terminal of a condenser 147. The other terminal of the condenser 147 is connected to the other terminal of the battery 123 through ground. A circuit is likewise completed from one terminal of the battery 123, through the conductor 144, the resistance 145, a second resistance 148 similar to resistance 146, a condenser 149 similar to condenser 147, and through ground, to the other terminal of the battery 123.

By means of the circuit described above, the condensers 147 and 149 are kept charged. Accordingly, when the upper terminal of either polar relay winding 127 or winding 142 is connected to ground, by means of the synchronous motor 108 or the electric clock 110, the condenser to which the winding is connected discharges through that winding. This momentary flow of current through the winding is sufficient to pull the armature 125 against a contact. Because of this arrangement, the armature 125 of the polar relay 124 may be pulled away from a contact very

shortly after it is pulled against it, since the rush of currents lasts a very short time. Therefore, the armature 125 of the relay may be pulled away from a relay contact even though the contacts of the synchronous motor 108 or electric clock 110, which pull the armature 125 against the relay contact are still closed.

The condensers 150 and resistances 151 are employed to reduce sparking at the relay contacts.

The following values of capacity, resistance, and voltage have been found satisfactory although, obviously, other values may be employed if desired: resistances 146 and 148 equal 5 megohms; resistance 145 equals 1000 ohms; resistance 112 equals 50 ohms; resistance 116 equals 800 ohms; resistance 118 equals 20 ohms; condensers 147 and 149 equal .25 micro-farads; resistance 121 equals 10,000 ohms; and voltage of battery 123 equals 350 volts.

The operation of the circuit will be more fully understood by referring to the diagram of Fig. 6 which greatly exaggerates the rapidity with which changes in the fork frequency occur. In this diagram, the current applied to the fork heater 69 is plotted against time in seconds. From zero to four seconds, the generator is supplying a current of the proper frequency, that is, 5,000 cycles per second. Accordingly, the fork heater 69 is alternately connected to, and disconnected from, the current supply at one-second intervals. When the fork 84 begins to vibrate too slowly, the synchronous motor 108 slows down, and, after the heater 69 has been disconnected from the current supply (as after the four-second interval) it is not again connected to the current supply until a longer time than one second. The electric clock 110, however, is not affected by the frequency of the tuning fork 84, and continues to disconnect the current from the fork heater 69 at two second intervals. The current supply is accordingly disconnected from the heater 69 at the six-second interval. It will be noted from the diagram that, as a result, less heat is applied to the fork 84 than when it is vibrating at the proper frequency. Accordingly, the tuning fork 84 will be cooled slightly and its frequency will increase. In the diagram, the fork frequency begins to increase after the ten-second interval. After the twelve-second interval, the fork 84 begins to vibrate too rapidly, and the synchronous motor 108 speeds up. This results in heat being applied to the fork 84 an instant sooner than it would be if the fork were vibrating at the 5000-cycle frequency. The temperature of the fork 84 is, accordingly, increased and its frequency is changed the desired amount.

It will be noted that, at the sixteen-second interval, the fork 84 is vibrating so rapidly that the synchronous motor 108 connects the heater 69 to the current supply as soon as it is disconnected by the electric clock 110. It is evident that, if the fork 84 vibrates still more rapidly, the synchronous motor speed will be so high that its contact 130 connects the fork heater 69 to the current supply just before the contacts of relay 139 are closed by the electric clock 110 to disconnect the current supply from the heater. When this happens, less, instead of more, heat is applied to the fork 84 than is applied when it runs at the proper frequency, and the system will not correct the fork frequency. In such a case, a manual adjustment must be made to increase the fork temperature. Under ordinary conditions, no such adjustment is necessary. In the 5000-cycle generator described, the synchronous motor 108

connects the fork heater 69 to the current supply every 10,000 cycles, while the electric clock 110 disconnects the fork heater 69 from the current supply every two seconds.

5. Various modifications may be made in my invention without departing from the spirit and scope thereof and I desire, therefore, that only such limitations shall be placed thereon as are imposed by the prior art and set forth in the appended claims.

I claim as my invention:

1. In television apparatus, a scanning device comprising a disc and means comprising a plurality of projections disposed in circular formation

15 on said disc whereby the disc functions as a part of the rotor of a synchronous motor.

2. In television apparatus, a scanning device comprising a rotatable disc and a rotor element of a synchronous motor disposed coaxially with

20 said disc and supported thereby.

3. In television apparatus, a scanning device comprising a rotatable element and a rotor element of a synchronous motor directly supported thereby.

25 4. In television apparatus, a scanning device

comprising a disc, the disc being provided with peripheral projections adapted to cooperate with a field winding to provide motive power for said disc.

5. In television apparatus, a scanning device 5 comprising a disc which is rotatable about its axis and which has light-transmitting openings disposed therein near its periphery, and a synchronous-motor rotor comprising a circular magnetic element having teeth projecting from its 10 periphery, said rotor being supported by said disc and disposed with its teeth a greater distance from the axis of said disc than are said openings.

6. In television apparatus, a scanning device 15 comprising a rotatable disc, a rotor of a synchronous motor disposed coaxially with said disc and supported thereby, said rotor comprising a circular element of magnetic material having teeth projecting from its periphery, and a synchronous 20 motor stator comprising poles supported in co-operative relation with said rotor for a portion only of its circumference.

FRANK CONRAD. 25
